UNITED STATES PATENT OFFICE.

JOHN C. GILLETTÉ, OF LAKWOOD, OHIO, ASSIGNOR, BY MESNE ASSIGNMENTS, TO NATIONAL CARBON COMPANY, INC., A CORPORATION OF NEW YORK.

APPARATUS FOR SECURING BINDING-POSTS TO ELECTRODES.

1,287,669.

Specification of Letters Patent.

Patented Dec. 17, 1918.

Application filed February 27, 1917. Serial No. 151,382.

To all whom it may concern:

Be it known that I, JOHN C. GILLETTÉ, a citizen of the United States, residing at Lakewood, in the county of Cuyahoga and State of Ohio, have invented a certain new and useful Improvement in Apparatus for Securing Binding-Posts to Electrodes, of which the following is a full, clear, and exact description.

This invention relates to apparatus for securing to carbon electrodes, binding posts of the type described in the Henn Patent 813,093.

The usual method of inserting these posts or dowels requires two operators, one for drilling the electrodes and a second for pressing the dowels in the hole made therein.

The chief object of the invention is to provide apparatus controlled by a single operator for performing both the drilling and inserting operations.

Other objects of the invention will appear in the following description.

In the accompanying drawings illustrating one embodiment of my invention:

Figure 1 is a front view of the apparatus.

Fig. 2 is a plan view.

Fig. 3 is a rear view.

Fig. 4 is a cross section on the line A—A of Fig. 1 looking in the direction of the arrows.

Fig. 5 is a cross section on the line B—B of Fig. 1 looking in the direction of the arrows.

Fig. 6 is an end view of an electrode holder with a carbon fitted therein.

Fig. 7 is a cross section on the line C—C of Fig. 6.

Fig. 8 is a section with parts broken away illustrating the dowel feed hopper and inclined chute.

Fig. 9 is a detached section showing the dowel release.

Fig. 10 is a view of the parts shown in Fig. 9 taken in the direction of the arrow.

Fig. 11 is a cross sectional view of a portion of the dowel feed slide.

Fig. 12 is an enlarged front view of the head stock end of the apparatus.

As shown in Figs. 1 and 4, the supporting framework consists of a bed 1 having a plurality of legs 2. The bed is provided with two projecting guides 3 running lengthwise thereof. Two bearings 4 are attached to one end of the bed and serve to carry the

shaft 5 of drive pulley 6. A chuck 7 for drill 8 will be fitted on the end of shaft 5. Projection 9 attached to the bed near the drill chuck serves to support a horizontal flat spring strip 10. The free end 11 which 60 is offset from the body portion 10 by means of a curved surface 12 is provided with a projecting pin 13 for a purpose to be referred to farther on.

A carriage 14 having grooves fitting on 65 the guides 3 is adapted to slide on the bed 1. A counterweight 15 attached to a cable 16 passing over pulley 17 exerts a force tending to draw the carriage 14 toward the drill 8. A second cable 18 fastened to the base 14 70 runs over a pulley 19 and is attached to a pivoted foot lever 20.

The carriage is also connected to a pivoted lever 21 which is connected by means of the rod 22 with a piston 23 movable in cylinder 75 24. The cylinder has an inlet 25 connected by a pipe (not shown) with a port 26 of a control valve 27 and an exhaust 28 connected to the port 29 of the control valve. The control valve is provided with an exhaust 80 port 30 and an inlet port 31 connected to any source of pressure such as a tank of compressed air (not shown).

The end of the carriage adjacent the drill will be provided with an upright abutment 85 32 having an opening 33 adapted to permit the drill 8 to pass therethrough. A slot 34 in carriage 14 is adapted to receive the base 35 of a turret 36 rotatable on a vertical shaft 37. A lever 38 having a controlling handle 90 39 fitted to the shaft, engages the spring 10 and cooperates with the curved portion 12 of the spring to rotate the turret. The turret attachment is practically the same as the attachment used in connection with an ordinary lathe and the internal construction for indexing the body portion 26 will not be described herein as such arrangements for indexing are old and well known.

Six holders, such as shown in Figs. 6 and 100 7, are carried by the turret body at points 60° apart, as indicated at A, B, C, D, E and F of Fig. 2. Each holder consists of a member 41 fitted into a projection 42 of the turret. A clamping arm 43 pivoted in a slot 105 44 in the projection, rests on the carbon electrode 45 when it is placed in the member 41 which may be channel-shaped or any other shape adapted to receive the electrode. At two points of the arm 43, clips 46 are at- 110

tached having depending ends fitted over the carbon retaining member 41. The clamping member 43 will be pressed against the electrode by means of springs 47, 47 arranged 5 on each side of the electrode support. Each spring is attached at one end to a projection 48 of the support 41 and at the other end to a cross bar 49 resting on the clamping arm. A sloping lug 50 projecting from 10 member 41 is provided for a purpose to be referred to later.

The dowel feeding device is supported from the frame by brackets 51 and comprises a box-like receptacle 52 having grooves 53 15 at opposite sides serving as guides for a reciprocating slide 54. The lower end of the slide is connected to a reciprocating arm 55 by means of a pin 56 fitted in slot 57. The upper movement of the slide is limited by 20 the stops 58. An inclined slot 59 is cut in the center of the slide to catch the dowels therein. When at the upper end of the stroke, the slot of the slide coincides with a slot 60 of the box 52 and is in alignment 25 with a slotted guideway 61 which passes through a second box 62. A pin 62' projects from the side of box 62 and engages the ends of dowels which are upside down, because the portion of the dowel that fits 30 in the carbon is longer than the threaded portion which is able to pass under the pin.

The mechanism for releasing one dowel at a time is attached to one side of the slotted guide 61 and consists of a block 63 35 (Fig. 9) bolted thereto having an edge projecting over the guide. Two blades 64, 65 pass through openings which are directly over the slot of the guide 61 and are spaced apart a distance equal to or less than the distance between adjacent dowels. The blades 40 are connected to reciprocating rods 66, 67 (Figs. 9 and 10) having their lower ends pivotally fastened to opposite arms 68, 69 of a T shaped member 70. The T 45 70 is pivoted at 71 to the inclined guide and has a flexible strip 72 attached to the lower end. The strip has a counterweight lug 73 at the free end which is engaged by a pin 74 projecting from the arm 55 which operates the 50 dowel feed slide.

The flange of the dowels slides on the upper edge of the guides in the upper part, but as shown in Fig. 11, a slot 75 on the inner surface of each side of the slot of guideway 61, is adapted to receive the flanged head as the dowel approaches the vertical portion 76 of the guide. The lower end of 55 the guide fits between a pair of arms 77 (Fig. 4) pivoted on a bolt 78'. The adjacent 60 faces of the arms, when in a closed position as shown, form a passage 78 similar in section to that of the lower part 76 of guideway 61 which connects therewith. The combined passage serves for leading the dowels 65 to a position in which they are in alignment

with the adjacent carbon electrode fitted in the holder. The passage 78 is open at the front and back so that the ends of the dowel project therethrough. A small slot 79 is provided for the head of the dowel. To hold 70 the arms 77 together a spring 80 is used which is fastened between pins 81 on the arms. A wedge 82 movable in a space 83 between the arms, serves to spread these apart. The wedge is mounted on the end 75 of a pivoted lever 84 having an upstanding lug 85 adapted to be engaged by the lug 50 on the bottom of the electrode support to force the wedge 82 downward.

The supporting framework for arms 77 80 and the wedge consists of a block 86 (Fig. 1) having two rods 87 (Fig. 5) extending to the back 88 of a head stock 89 mounted on the frame. The block 86 may be moved under the action of springs 90 which are placed 85 around rods 87 between the block and the head stock. Bolt 78' serving as pivot for arms 77, also connects these to the block 86. The pivoted lever 84 is mounted between lugs 91 of a frame 92 that is connected to 90 block 86 by bars 93. At the lower end of frame 92 rollers 94 are attached which move on the bed 1. Stops 95 limit the movement of the upper end of arms 77 so that the slots of the guide and the arms come into alignment.

The dowel retaining arms 77 and connected parts are adapted to be moved back and forth to insert the threaded end of the dowel in an opening 96 of a plunger 97 100 slideable in the head stock 89. This movement is produced by means of a linkwork consisting of a strip 98 attached to block 86 and passing through the back 88, and connected to an arm 99 keyed on a shaft 100. A second link 101 fastened on axis 100 is pivotally joined to link 102. An operating lever 103 is pivotally connected at an intermediate point 104 to a lug 103'. Link 102 is connected at one end to the lever 103 and the other end of this lever is adapted to engage a cam slot 104' of the carriage 14. 110

The head stock plunger 97 is movable against an arm 105 pivoted at 106. Movement of the plunger is opposed by a compression spring 107 fitting around a rod 108 projecting from a supporting lug 109 of the head stock. The end 110 of lever 105 slides in a yoke 111 attached to lug 109 and when plunger 99 is moved a sufficient distance the end 110 engages a contact point 112 insulated from the yoke 111. 115

One terminal of an electric circuit is connected to the contact 112 and the other is connected to a lamp 113 which is electrically connected with the bed 1. 120

The dowel feed lever 55 is pivoted at 114 and connected to an upstanding arm 115 of a rod 116. This rod passes through a lug 117 on the base 14 and has a spring 120 130

placed thereon between the lug 117 and a stop 121 and a second spring 118 between stop 119 and lug 117. The dowels used have a long portion 122, a short threaded portion 5 123, and a collar 124 between the two.

To facilitate the understanding of the operation it will be assumed that the machine has been in operation long enough to have drilled holes in all the electrodes excepting those in positions C and B. It will also be assumed that the carriage 14 has just been released and is traveling back toward the left in Fig. 2. The operation is then as follows:—

15 The hopper 52 is kept supplied with dowels by placing a number of them therein from time to time. The drill 8 is maintained in continual rotation unless it is desired to shut down the apparatus.

20 The operator removes the doweled electrode from position A and inserts a fresh one as the carriage travels backward toward the left under the influence of counterweight 15. The carbon will be pushed under the 25 arm 43 and pressed back until it abuts against the projection 42 where springs 47 hold it quite rigidly. The electrode in position C is forced against drill 8 to drill the hole therein until the cross piece abuts 30 against the drill chuck. The operator then pushes downward on lever 20 and pulls the carriage to the right until the drilled electrode in position F is forced against the dowel in holder 77. Instead of relying on 35 foot pressure to force the dowel into the electrode, the operator preferably operates air valve 27 and admits pressure into cylinder 24 to complete the movement of the carriage to the right. During the return movement to the right as just described, arm 38 40 slides along on the spring cam 10 until it engages the pin 13. Further movement of the turret therefore rotates the arm 38 in a counter clockwise direction, but this produces no movement of the turret on account 45 of the chuck indexing arrangement not shown.

When the electrode is forced against the dowel the reaction through the plunger 27 50 will compress spring 108 and force back lever 110 until contact is made at 112, providing that the relation between the size of the dowel and the size of the hole in the electrode is sufficient to make a tight connection. The electric lamp 113 will therefore light up and the operator will know that the dowel has been properly inserted. He will release pressure on lever 21 at this point and permit the counterweight to draw 55 the carriage again to the left in Fig. 2.

If lamp 113 did not light up during the doweling operation, this would indicate that the dowel was forced into the electrode against insufficient resistance or else spring 60 107 would have been compressed sufficiently

to make contact at 112. In case the lamp does not light up as just described, the operator will discard the electrode as having imperfect connection.

At the beginning of the movement of the 70 turret toward the drill, the end of lever 38 is caught in the curved part 12 of the spring 10 and the arm and turret are moved through 60°, in a clockwise direction by indexing mechanism within the turret to the 75 position shown in Fig. 2. The end of the lever then rides on cam spring 10 as shown in this figure. The operator then removes doweled electrode in position A and inserts a fresh one during the backward movement 80 of the carriage.

The manner in which the dowels are fed into the chuck member 77 after each insertion will now be described.

As the turret base moves toward the drill 85 the dowel feed is operated when lug 117 presses spring 120 toward the stop 121. The rod 116 and attached connecting member 115 are thus moved toward the drill whereby the end of pivoted lever 55 is raised. A dowel 90 will be released and will be held in position in arms 77 to enter the carbon when the pin 74 raises the arm 55 and the front strip 65 sufficiently to release the dowels. The rear strip 64 enters the space between dowels before 95 the front strip releases them, and holds back all but the front dowel which occupies a position between the blades. The dowel slides down the inclined guideway 61 and before reaching the vertical part 76 the head 100 124 enters the groove 75 and then continues downward, passing into the space 78 between the arms 77. The head is retained in the groove 79 and when the dowel reaches the bottom of the space 78 between the arms 105 77 one end 122 is in alinement with the carbon, and the screw threaded end 123 is adjacent hole 96 in the plunger 97. Movement of lever 55 also raises slide 54 which passes through the dowels in the box 53 and some 110 of these will be caught in slot 59. Upon reaching the slot of the guideway 61 the dowels will slide down the inclined surface as far as the reciprocating blade 64. Any dowels delivered to the slide 61 with the 115 long portion 124 up, will be knocked out of the slide into the receptacle 62 or will be reversed by the pin 63'. The dowels will then slide down the incline until the lowest one reaches the blade 64 which is moved in the 120 position shown in Fig. 9 during the drilling. This movement is produced when the carriage moves toward the drill, whereby the lever 55 is raised by the engagement of pin 74 with the lug 73 of spring 72.

After the drilling operation is completed 125 the operator will move the turret in the other direction by pressing on foot lever 20 as previously described. The dowel and its retaining arms 77 will be moved by means 130

of arm 98 toward the plunger 97 so that the threaded pin 123 enters the hole 96. The arm 98 is moved backward when the inclined surface 104' of the turret base 14 strikes the end of lever 102. The operator will maintain the foot pressure until the tip of the dowel enters the carbon. At practically the same time that the dowel enters the carbon the arms 77 are spread 10 apart so that the dowel is supported by plunger 97 and the carbon. This is done by cam 50 which engages projection 85 to move the wedge 82 down between the arms. When the hole of the electrode in position F 15 reaches the tip of the dowel, the operator will apply air pressure to piston 23 to force the dowel the rest of the way into the carbon. The air pressure will not be applied unless the dowel is properly aligned with the 20 carbon.

Although the apparatus has been described as consisting of manual and pneumatic means for forcing the dowels in the carbons, it will be evident that either could 25 be used alone, although the combination is preferable, because it is difficult to have the dowels and drill holes accurately aligned in every case. This is essential because if air pressure only is used the carbon will be split 30 if the dowel does not enter the drilled hole.

Having described my invention, what I claim is:

1. In apparatus for inserting a dowel terminal in an electrode, a holder for the electrode, a rotating drill adapted to engage said electrode to form a bore, a holder for a dowel and means for placing said electrode successively adjacent said drill and dowel holder.

2. In apparatus for inserting dowel terminals in electrodes, a plurality of holders for electrodes, a drill adapted to successively engage the electrodes, a holder for a dowel and means for moving said electrodes successively adjacent the dowel holder.

3. In apparatus for inserting dowel terminals in electrodes, a rotatable support having a plurality of electrode holders, a drill adapted to successively engage the electrodes, a holder for a dowel, means for feeding a dowel thereto and means for moving said electrodes successively adjacent the dowel holder.

4. In apparatus for inserting dowel terminals in electrodes, a rotatable support having a plurality of electrode holders, a drill adapted to successively engage the electrodes, a holder for a dowel, means for feeding the dowel thereto, and means for placing said drill and said dowel holder in engagement with each electrode holder.

5. In apparatus for inserting dowel terminals in electrodes, a supporting frame, a base slidably mounted thereon having a plurality of holders adapted to retain an elec-

trode, a rotating drill, a dowel holder mounted on the frame, means for feeding a dowel to the holder and means for moving the base into engagement with the drill or dowel holder.

6. In apparatus for inserting dowel terminals in electrodes, a supporting frame, a base slidably mounted thereon, a rotatable turret mounted on said base having a plurality of holders projecting therefrom adapted to retain an electrode, a rotating drill attached to the frame, a dowel holder, means for feeding a dowel to the holder and means for moving said turret alternately into engagement with said drill and dowel holder.

7. In apparatus for inserting dowel terminals in electrodes, a supporting frame, a base slidably mounted thereon, a rotatable turret mounted on said base having a plurality of holders projecting therefrom adapted to retain an electrode, a rotating drill attached to the frame, a dowel holder, a hopper containing a plurality of dowels, a reciprocating slide for removing dowels from the hopper, a guideway for conveying dowels from the slide to said holder and means for moving said turret alternately into engagement with the drill and dowel holder.

8. In apparatus for inserting dowel terminals in electrodes, a supporting frame, a base slidably mounted thereon, a rotatable turret mounted on said base having a plurality of holders projecting therefrom adapted to retain an electrode, a rotating drill, a dowel holder, a member having an opening adapted to receive one end of a dowel, means for moving the dowel holder whereby the dowel enters said opening, means for moving the turret toward the dowel holder and means for releasing the dowel when it enters the electrode.

9. In apparatus for inserting dowel terminals in electrodes, a supporting frame, a base slidably mounted thereon, a rotatable turret mounted on said base having a plurality of holders projecting therefrom adapted to retain an electrode, a rotating drill, a dowel holder, a member having an opening adapted to receive one end of a dowel, means for moving the dowel holder whereby the dowel enters said opening, means for moving the turret toward the dowel holder, means for releasing the dowel when it enters the electrode and means for yieldingly resisting movement of the turret toward the dowel holder.

10. In apparatus for inserting dowel terminals in electrodes, a supporting frame, a base slidably mounted thereon, a rotatable turret mounted on a base having a plurality of holders projecting therefrom adapted to retain an electrode, a rotating drill, a dowel holder, a member having an opening adapted

- to receive one end of a dowel, means for moving the dowel holder whereby the dowel enters said opening, means for moving the turret toward the dowel holder, means 5 for releasing the dowel when it enters the electrode, means for yieldingly resisting movement of the turret toward the dowel holder and means operated by said yieldingly resisting means adapted to indicate 10 the movement of said last mentioned means.
11. In apparatus for inserting dowel terminals in electrodes, a supporting frame, a base slidably mounted thereon, a rotatable turret mounted on a base having a plurality 15 of holders projecting therefrom adapted to retain an electrode, a rotating drill, a dowel holder, a member having an opening adapted to receive one end of a dowel, means for moving the dowel holder whereby the dowel 20 enters said opening, means for moving the turret toward the dowel holder, means for releasing the dowel when it enters the electrode, means for yieldingly resisting movement of the turret toward the dowel holder, 25 means operated by said yieldingly resisting means adapted to indicate the movement of said last mentioned means, an electric circuit and an arm operated by said yieldingly resisting means to close the electric circuit.
12. In apparatus for inserting dowel terminals in electrodes, a hopper for the dowels, a slide reciprocating therein adapted to engage the dowels, a conveyer for receiving the dowels therefrom, a holder for a dowel, 30 a holder for an electrode, means for moving the holder toward the dowel and means for yieldingly resisting said movement.
13. In apparatus for inserting dowel terminals in electrodes, a holder for retaining a 35 dowel, means for feeding dowels singly thereto, a holder for an electrode, means for moving the holder toward the dowel and means for yieldingly resisting said movement.
14. In apparatus for inserting dowel terminals in electrodes, a hopper for the dowels, 40 a slide reciprocating therein adapted to engage the dowels, a conveyer for receiving the dowels therefrom, a holder for a dowel, means for releasing dowels one at a time to 45 said holder, a holder for an electrode, means for moving the holder toward the dowel, means for yieldingly resisting said movement and means for releasing the dowel from the holder when it is engaged by said yieldingly resisting means and said electrode.
15. In apparatus for inserting dowel terminals in electrodes, a hopper for the dowels, a slide reciprocating therein adapted to engage the dowels, a conveyer for receiving the 50 dowels therefrom, a holder for a dowel, means for releasing dowels one at a time to said holder, a holder for an electrode, means for moving the electrode holder toward the dowel holder, means for yieldingly resisting 55 said movement, means for moving said dowel holder toward the yielding resisting means whereby it is fitted therein, and means for releasing the dowel from the holder when it is engaged by said yielding resisting means and said electrode.
16. In apparatus for inserting dowel terminals in electrodes, a hopper for the dowels, a slide reciprocating therein adapted to engage the dowels therefrom, a holder for a 60 dowel, means for releasing dowels one at a time to said holder, a holder for an electrode, means for moving the electrode holder toward the dowel holder, means for yieldingly resisting 65 said movement, means for moving said dowel holder toward the yielding resisting means whereby it is fitted therein, and means for releasing the dowel from the holder when it is engaged by said yielding resisting means and said electrode.
17. In apparatus for inserting dowel terminals in electrodes, a hopper for the dowels, a slide reciprocating therein adapted to engage the dowels therefrom, a holder for a 70 dowel, means for releasing dowels one at a time to said holder, a holder for an electrode, means for moving the electrode holder toward the dowel holder, means for yieldingly resisting 75 said movement, means for moving said dowel holder toward the yielding resisting means whereby it is fitted therein, and means for releasing the dowel from the holder when it is engaged by said yielding resisting means and said electrode.
18. In apparatus for inserting dowel terminals in electrodes, a hopper for the dowels, a slide reciprocating therein adapted to engage the dowels therefrom, a holder for a 80 dowel, means for releasing dowels one at a time to said holder, a holder for an electrode, means for moving the electrode holder toward the dowel holder, means for yieldingly resisting 85 said movement, means for moving said dowel holder toward the yielding resisting means whereby it is fitted therein, and means for releasing the dowel from the holder when it is engaged by said yielding resisting means and said electrode, an electric circuit and an arm operated by said yieldingly resisting means adapted to close the electric circuit when sufficient force is applied to the arm.

In testimony whereof, I hereunto affix my 90
signature.

J. C. GILLETTE.
